(57) **CLAIM**

The ornamental design for an intradermal needle, as shown and described.

DESCRIPTION

FIG. 1 is a back, right side perspective view showing my new design, wherein the back, left side perspective view is a mirror image thereof;

FIG. 2 is a top plan view thereof, wherein the bottom plan view is a minor image thereof;

FIG. 3 is a left side elevation view thereof, wherein the right side elevation view is a mirror image thereof;

FIG. 4 is a back side elevation view thereof; and,

FIG. 5 is a front side elevation view thereof.

The intradermal needle is shown with a symbolic break in its length, with the understanding that the portions of the device not shown in the drawings form no part of the claim design. Patentability is based only on those portions of the article that are shown in solid lines.
